(57) CLAIM

The ornamental design for a display for a rifle, as shown and described.

DESCRIPTION

FIG. 1 is a plan view of a display embodying my design;
FIG. 2 is a left side elevation view thereof;
FIG. 3 is a front elevation view thereof;
FIG. 4 is a right elevation view thereof;
FIG. 5 is a perspective view of the display; and,
FIG. 6 is a front elevation view of the display showing a rifle
displayed thereon in phantom line, the rifle not being part of
the claimed design.
